(57) **CLAIM**

The ornamental design for a handle for a pan or a similar kitchen utensil, as shown and described.

DESCRIPTION

FIG. 1 is a top plan view of a handle for a pan or similar kitchen utensil showing my new design;

FIG. 2 is a bottom plan view thereof;

FIG. 3 is a front perspective view thereof;

FIG. 4 is a side perspective view thereof;

FIG. 5 is a rear perspective view of the inner portion of the handle;

FIG. 6 is a side perspective view of the outer portion of the handle; and,

FIG. 7 is an opposite side perspective view of FIG. 6.

FIGS. 5-7, showing the two parts of the handle, are shown separately for clarity of illustration.

The handle consists of a metal part and a plastic part. The metal part is u-shaped in a first plane and ends in two mounting parts.
